Primary Examiner — T. Chase Nelson*Assistant Examiner* — Michelle E Wilson(74) *Attorney, Agent, or Firm* — George H. Leal; Andrew J. Mueller(57) **CLAIM**

The ornamental design for an absorbent article, as shown and described.

DESCRIPTION

FIG. 1 is a perspective view of an embodiment of an absorbent article showing our new design;

FIG. 2 is a top view of the absorbent article of FIG. 1, but shown in a flattened condition;

FIG. 3 is a bottom view of the absorbent article as shown in FIG. 2;

FIG. 4 is a left side view of the absorbent article as shown in FIG. 2;

FIG. 5 is a right side view of the absorbent article as shown in FIG. 2;

FIG. 6 is a front side view of the absorbent article as shown in FIG. 2;

FIG. 7 is a back side view of the absorbent article as shown in FIG. 2;

FIG. 8 is a perspective view of a second embodiment of an absorbent article showing our new design; and,

FIG. 9 is a top view of the absorbent article of FIG. 8, but shown in a flattened condition.

The broken lines show portions of the absorbent article that form no part of the claimed design.

1 Claim, 9 Drawing Sheets---
